UNITED STATES PATENT OFFICE

150,051

DESIGN FOR A HAND CARRIED SUPPORT FOR LIGHTING AND CAMERA MEANS

Arthur L. Bensen, West New Brighton,
Staten Island, N. Y.

Application March 18, 1947, Serial No. 137,723

Term of patent 14 years

(Cl. D61—1)

To all whom it may concern:

Be it known that I, Arthur L. Bensen, a citizen of the United States, residing at West New Brighton, Staten Island, in the county of Richmond and State of New York, have invented a new, original, and ornamental Design for a Hand Carried Support for Lighting and Camera Means, of which the following is a specification, reference being had to the accompanying drawing, forming part thereof.

The figure is a perspective view of a hand carried support for lighting and camera means showing the essential features of my design in full lines, the broken lines being for illustrative purposes only.

I claim:

The ornamental design for a hand carried support for lighting and camera means, substantially as shown and described.

ARTHUR L. BENSEN.
